CHARLES E. DOTY, OF YONKERS, AND MICHAEL BIMONTE, OF NEW YORK, N. Y.

RAILWAY SWITCH

Application filed October 17, 1927. Serial No. 226,585.

This invention relates to railway switches, and more particularly to the securing of the stationary end of a switch point so as to permit a slight movement thereof to facilitate the required movement of the free end of the switch point, and to a new track bolt for fastening the joint bars in desired relation to the switch point.

The stationary or heel ends of switch points are customarily connected to the abutting end 10 of the fixed rail by angle bars or other joint bars, and in order to permit the switch point to be moved readily by the means now used for that purpose, it has been customary not to bolt the angle bars tightly against the switch point but to leave the nuts on the bolts somewhat loose so as to permit a slight freedom of movement of the heel of the switch point. This is not good practice, however, and the 20 object of the present invention is to provide for such desirable slight freedom of movement of the heel end of the switch point without the necessity of having any loose bolts.

A full understanding of the invention can best be given by a detailed description of a 25 switch point connection and track bolt according to the invention, and such a description will now be given in connection with the accompanying drawings, in which:—

Fig. 1 is a view partly in elevation and 30 partly in section of a track bolt according to the invention;

Fig. 2 is a plan view of the abutting end 35 portions of a fixed rail and a switch point and connecting means according to the invention, sectioned on a horizontal plane; and

Figs. 3 and 4 are sectional views taken, respectively, on lines 3—3 and 4—4 of Fig. 2.

Referring to the drawings, Fig. 2 shows 40 portions of a fixed rail 10 and of a movable switch rail, or switch point, 11 extending from the end of the fixed rail and connected thereto by means of angle bars 12 and 13 placed one on each side of the rail and switch point. The portions of the angle bars which 45 extend past the end of the fixed rail are secured in the usual manner by bolts 15 extending through holes in the angle bars and in the web of the rail, the nuts on these bolts 50 being turned down so that the ends of the

angle bars are clamped tightly against the rail, as most clearly shown in Fig. 4. The other end of the angle bars which extend past the end portion of the switch point, instead of being clamped tight against this 55 switch rail, are secured rigidly with relation to each other but spaced slightly away from the rail, as most clearly shown in Fig. 3, by means of special bolts 20 of the form shown in Fig. 1. These bolts 20 are, as shown, 60 threaded on both ends and have a fixed collar 21 most desirably formed integral with the bolt and which is offset from the middle of the bolt toward one end thereof. The thread on the other end of the bolt is extended to 65 near the middle of the bolt and a nut 22 screwed on to this end of the bolt provides an adjustable collar, the fixed collar 21 and this adjustable collar 22 serving to provide relatively adjustable shoulders to cooperate with 70 the nuts 23 and 24 screwed on the respective ends of the bolt.

In securing the angle bars to the end of the switch point according to the invention by 75 means of the new bolts, each bolt with the nuts removed is inserted through one of the bolt holes in the web of the switch point and the inner nut 22 is screwed on to the bolt and adjusted to a position in which the distance 80 between the shoulders formed by the outer faces of the collar 21 and nut 22 is such that the angle bars bearing against these shoulders will be held spaced apart so as to be slightly out of engagement with the switch point. 85 The angle bars having been placed in position, the nuts 23 and 24 are then placed on the bolt and turned down to clamp the angle bars tightly between them and the respective shoulders provided by the collar 21 and nut 22. The angle bars will thus take a position 90 as shown in Fig. 2 in which they extend at a slight angle to each other diverging from the fixed rail end of the bars to the opposite end. The bars will be held rigidly in this position 95 relatively to each other, and being spaced slightly out of engagement with the switch point, the heel end switch point will be permitted to have the slight freedom of movement laterally which is desirable in order to 100

avoid too great resistance to the required shifting movement of the switch point.

All of the two or three or more bolts by which the angle bars are connected to the end of the switch point may be of the new form as shown, or the end bolt only may be of this form, ordinary bolts 15 being used in the other positions, the end bolt then serving to hold the ends of the angle bars spaced the desired distance apart, and these inner bolts being tightened to any desired degree. Any slight inward bending of the angle bars which may result from the use of ordinary bolts in these inner positions will not result in a too rigid 15 clamping of the end of the switch point so long as the ends of the angle bars are held spaced slightly apart by means of one of the bolts 20 or by other suitable means.

It is to be understood that the invention is 25 not to be limited to the exact embodiment shown, but that it includes changes and modifications within the claims. For example, the spacing bolts need not be of the exact form shown, and other means may be employed for 30 securing the joint bars spaced away from the switch point and permitting slight lateral movement of the switch point between the joint bars.

What is claimed is:

30 1. In a railway switch, the combination 95 with a fixed rail and a movable switch point, of joint bars connecting the heel end of the switch point to the abutting end of the fixed rail, one joint bar extending on each side of 35 the rail and switch point, fastening means 100 clamping the joint bars against the fixed rail, and fastening means rigidly holding the other end of the joint bars spaced slightly away from the switch point to permit slight lateral 40 movement of the switch point between the joint bars.

45 2. In a railway switch, the combination 105 with a fixed rail and a movable switch point extending from the end of the fixed rail, of joint bars extending one on either side of the adjacent end portions of said rail and switch point and bolted tight against the rail, and a bolt extending through holes in the joint bars and through a hole in the web of the 50 switch point and having nuts and cooperating shoulders by which the joint bars are 110 rigidly connected and held spaced slightly away from the switch point, whereby the switch point is given a slight freedom of 55 movement laterally.

60 3. In a railway switch, the combination 115 with a fixed rail and a movable switch point extending from the end of the fixed rail, of joint bars extending one on either side of the adjacent end portions of said rail and switch point and bolted tight against the rail, a spacing member extending between the joint bars through a hole in the web of the switch point by which the joint bars are held slightly 65 away from the switch point, and means hold- 120

ing the joint bars tight against said spacing member, whereby the switch point is given a slight freedom of movement laterally.

4. In a railway switch, the combination 70 with a fixed rail and a movable switch point extending from the end of the fixed rail, of joint bars extending one on either side of the adjacent end portions of said rail and switch point and bolted tight against the rail, and a bolt extending through holes in the joint bars 75 and through a hole in the web of the switch point, said bolt being threaded at both ends, having a fixed collar near one end and an adjustable collar near the other end, and having a nut on each end to co-operate with the fixed 80 collar and the adjustable collar respectively to hold the joint bars rigidly connected and spaced slightly away from the switch point, whereby the switch point is given a slight 85 freedom of movement laterally.

In testimony whereof, we have hereunto set our hands.

CHARLES E. DOTY.
MICHAEL BIMONTE.
